NEWSPAPER DELIVERY TUBE
Meade Monroe, Cleveland, Ohio, assignor to Newspaper
Enterprise Association
Filed June 11, 1962, Ser. No. 201,631
4 Claims. (Cl. 232—17)

This invention is a continuation-in-part of my co-pending application filed on October 16, 1959, Serial No. 846, 977 now Patent No. 3,047,213 entitled Newspaper Delivery Tube.

The present invention relates to an improved newspaper delivery tube structure that will protect and shield the newspaper placed therein from rain, snow, wind or other detrimental weather conditions while awaiting removal by the householder.

It has been found that the rain and melted snow and ice, because of surface tension, forms into separate drops or pools and remains so until the drops have increased in size sufficient to overcome such tension. Such raindrops may be $\frac{1}{8}$ of an inch or more in depth on the inner surface of the bottom wall of the tube. This means that the tube will maintain a moisture content for a long period pending the evaporation of the drops of rain. Since the paper used as newsprint is water absorbent this results in a wet portion of the newspaper where it comes into contact with such drops of water, even though the storm that caused the rain has subsided prior to the delivery of the newspaper. The present invention is designed to eliminate the water damage to a delivered paper.

A principal object of this invention is to provide a newspaper tube that will prevent the newspaper from coming into contact with rain water driven into the open end of the tube during storms or during inclement weather.

Another object of the invention resides in the improved drainage and hooded opening to receive the newspaper.

Still another object of the invention is a newspaper tube having one or more raised ribs to support the newspaper delivered therein extending the approximate length of the upper surface of the bottom wall of the tube.

Other objects and advantages of the invention reside in a structure which is economical of manufacture and maintenance as well as efficient of use.

Other objects and advantages more or less ancillary to the foregoing, and the manner in which all the various objects are realized will appear in the following description, which considered in connection with the accompanying drawings, sets forth the preferred embodiment of the invention.

Referring to the drawings:

FIG. 1 is a perspective view of the newspaper tube showing the closed rear end of the tube;

FIG. 2 is a fragmentary elevational-sectional view of the tube taken on a line 6—6 of FIG. 1 showing the rear portion of the tube;

FIG. 3 is a fragmentary elevational-sectional view of a tube taken on line 7—7 of FIG. 1 showing the hooded front open end portion of the tube.

FIG. 4 is a cross-section of the bottom wall of the tube taken on a line 8—8 of FIG. 3 showing the newspaper support ribs and drainage holes associated therewith;

FIG. 5 is a fragmentary plan view of the newspaper support ribs and drainage holes associated therewith as shown in FIG. 4.

Referring particularly to the drawings, the improved newspaper delivery tube may be made of plastic, such as polyethylene or other materials that are suitable for molding and weather resistant. It consists of two principal parts, i.e., the molded-elongated tube member 30 generally rectangular in cross-section, and the mounting bracket

2

(not shown). The said mounting bracket is shown in said co-pending application.

Referring now to the drawing it will be seen that the said tube 30 has an open front end 31 and a slightly smaller, closed rear end 32 which may best be seen by referring to FIGS. 1 and 2 of the drawing.

The said closed rear end 32 is positioned so as to form a right angle with the bottom wall 33 of the tube 30.

The said tube 10 has side walls 34 and 35 respectively and a top wall 36 that converge slightly from the said open end 31 toward the closed rear end 32.

In the drawing the closed rear end 32 has a centrally located flanged plastic disc 37 which seals an opening 38 left therein during the casting operation in molding the tube 30.

The said open end 31 has a hood 39 formed by an extension 40 of the top wall 36 beyond the vertical plane of the front edge 41 of the bottom wall 33 and corresponding oblique extensions 42 and 43 of the side walls 34 and 35.

As shown on said co-pending application, the bottom wall of the tube has a rectangular raised-ribbed bracket seat and attached bracket with drainage openings in the bottom wall of the tube adjacent thereto.

On the inner surface 44 of the bottom wall 33 are spaced-apart raised ribs 45 extending from the closed end 32 of the tube to a point adjacent the front edge 41 of the front end of the tube. Preferably the minimum height 46 of said ribs 45 should exceed the maximum depth of the rain drops that have collected during a rain storm on the said inner surface of the bottom wall 33.

Associated with the said raised ribs 45 are circular drainage openings 47 in the bottom wall 33 of the tube. The said drainage openings 47 are in axial alignment with said ribs 45 and preferably are placed adjacent the open front end 31 of the tube and near the rear closed end of the tube to provide drainage from the tube floor areas separated by the said raised ribs 45. The said drainage openings 47 have downwardly extending edges or beads 48 on the outer lower surface of said bottom wall 33 to provide a drip edge for the drainage water and thus prevent such water from moving upwardly by capillary attraction and thereby wet the newspaper contained within the tube.

Although the foregoing description is necessarily of a detailed character, in order that the invention may be completely set forth, it is understood that the specific terminology is not intended to be restrictive or confining, and that various arrangements of parts and modifications of detail may be resorted to without departing from the scope or spirit of the invention as herein claimed.

What is claimed is:

1. A newspaper delivery tube designed to be affixed to a support bracket therefor comprising:

- (a) a one-piece elongated hollow body generally rectangular in cross section and having a closed end substantially perpendicular to the longitudinal axis thereof, an open end, and a bottom wall having a substantially smooth upper surface,
- (b) spaced-apart ribs within said body and integral with said bottom wall and extending upwardly therefrom and from adjacent the open end of the body to adjacent the closed end thereof,
- (c) the said ribs being substantially rectangular in cross section and of sufficient vertical height to support a newspaper out of contact with water on the said upper surface of said bottom wall, and
- (d) at least one drainage opening through the said bottom wall and adjacent to each rib, each said opening extending beneath the adjacent rib and opening into the spaces on opposite sides of such rib so that the

water on either side of a rib may drain through the opening beneath that rib.

2. In a newspaper delivery tube designed to be affixed to a support bracket therefor as set forth in claim 1 in which there are downwardly extending beads on the lower surface of the said bottom wall surrounding the said drainage openings through said bottom wall to provide a drip edge for water which accumulates adjacent thereto.

3. A newspaper delivery tube designed to be affixed to a support bracket therefor as set forth in claim 1 in which the open end of said body lies in a plane oblique to the vertical so that the top edge thereof overlies the bottom edge thereof. 10

4. A newspaper delivery tube designed to be affixed to a support bracket therefor comprising:

(a) a one-piece elongated hollow body generally rectangular in cross section and having a closed end substantially perpendicular to the longitudinal axis thereof, an open end, and a bottom wall having a substantially smooth upper surface, 15

(b) the said open end lying in a plane oblique to the vertical so that the top edge thereof overlies the bottom edge thereof,

(c) spaced-apart ribs within said body integral with said bottom wall and extending upwardly therefrom

5

10

20

and from adjacent the open end of the body to adjacent the closed end thereof,

(d) the said ribs being substantially rectangular in cross section and of sufficient vertical height to support a newspaper out of contact with water on the said upper surface of said bottom wall,

(e) at least one drainage opening through the said bottom wall and adjacent to each rib, each said opening extending beneath the adjacent rib and opening into the spaces on opposite sides of such rib so that the water on either side of a rib may drain through the opening beneath that rib and,

(f) downwardly extending beads on the lower surface of said bottom wall surrounding said drainage openings to provide a drip edge for water that accumulates adjacent thereto.
